UNITED STATES PATENT OFFICE

144,639

DESIGN FOR A STALK CUTTER

Albert Henry Stockmar, Villa Rica, Ga.

Application August 14, 1945, Serial No. 121,429

Term of patent 14 years

(Cl. D40—1)

To all whom it may concern:

Be it known that I, Albert Henry Stockmar, a citizen of the United States of America, residing at Villa Rica, Georgia, have invented a new, original, and ornamental Design for Stalk Cutter, of which the following is a specification, reference being had to the accompanying drawings, forming part thereof.

In said drawings:

The essential features of my design are shown in full lines.

I claim:

The ornamental design for a stalk cutter, as shown and described.

ALBERT HENRY STOCKMAR.
